UNITED STATES PATENT OFFICE

98,050

DESIGN FOR AN ELECTRIC HEATER

Emery Brugh, Chicago, Ill., assignor to Moth
King Corporation, Chicago, Ill., a corporation
of Illinois

Application May 6, 1935, Serial No. 56,709

Term of patent 3½ years

To all whom it may concern:

Be it known that I, Emery Brugh, a citizen of the United States, residing at Chicago, in the county of Cook and State of Illinois, have invented a new, original, and ornamental Design for an Electric Heater, of which the following is a specification, reference being had to the accompanying drawing, forming a part, wherein:

Figure 1 is a perspective of an electric heater embodying the new design; and

Figure 2 is a side view of the heater; and
Figure 3 is a bottom view.

I claim:

The ornamental design for an electric heater, substantially as shown.

EMERY BRUGH.
